(57) **CLAIM**

The ornamental design for a packaging container for gels and the like, as shown and described.

DESCRIPTION

FIG. 1 is a perspective view of a container showing our new design;

FIG. 2 is front view of the container of FIG. 1;

FIG. 3 is a back view of the container of FIG. 1;

FIG. 4 is a right side view of the container of FIG. 1;

FIG. 5 is a left side view of the container of FIG. 1; and, FIG. 6 is a top view of the container of FIG. 1.

The broken line showing the bottom portion of the container in the FIGs. is for illustrative purposes only and forms no part of the claimed design.
